UNITED STATES PATENT OFFICE.

ANSON BORKERT, OF WARSAW, INDIANA.

OARLOCK.

Application filed March 11, 1927. Serial No. 174,553.

This invention relates to oar locks one of the objects being to provide a simple and efficient device which, when placed in position upon the side of a boat will support the 5 oar at a higher point than ordinarily so that it will not interfere with the movement of the knees of the oarsman.

A further object is to provide a device of this character which can be attached in position readily and which will be held in place firmly.

With the foregoing and other objects which will appear as the description proceeds, the invention resides in the combination and arrangement of parts and in the details of construction hereinafter described and claimed, it being understood that changes in the precise embodiment of the invention herein disclosed may be made within 20 the scope of what is claimed without departing from the spirit of the invention.

In the accompanying drawings the preferred form of the invention has been shown.

In said drawings,

25 Figure 1 is a side elevation of the device in position, a portion of the boat being shown.

Figure 2 is a section on line 2—2 Figure 1.
Figure 3 is a section on line 3—3 Figure 2.

30 Referring to the figures by characters of reference 1 designates an attaching plate which can be of any desired contour though preferably shaped as illustrated. This plate is provided, at its upper end with a transverse flange 2 and formed integral with the plate 1 and extending above the flange 2 is a bearing sleeve 3 supported outwardly beyond the plate 1. This sleeve has an opening 4 extending entirely through it and 35 the opening may be provided, for the greater portion of its length, with a bushing 5 of brass or other suitable metal. The pin 6 which extends from the yoke 7 of the oar lock is adapted to project into the sleeve and 40 to rotate within the bushing 5. This pin has a supporting collar 8 at its upper end constituting the base of the yoke, and said 45 collar is adapted to bear downwardly on the upper end of the sleeve 3.

50 In using this device the same is placed against the outer face of the side of the boat

a portion of which has been indicated at B so that the flange 2 will bear downwardly on the side. Suitable fastening means such as screws or bolts 9 are inserted through the 55 plate into the side of the boat and similar fastening means are inserted downwardly through the flange 2 as shown in Figure 3.

By providing the upstanding bearing sleeve 3 the yoke 7 is supported at such an 60 elevation that the oars, when operated, will not interfere with the movement of the knees of the user. As the opening 4 extends entirely through the sleeve water and sediment can not accumulate therein and, therefore, the pin 6 can rotate freely at all times. The bushing 5 is advantageous because it makes the pin 6 rotate more easily than would otherwise be possible. By providing 65 the plate 1 and the flange 2 with the separate 70 fastening means the oar lock can be more securely fastened to the side of the boat than would otherwise be possible.

What is claimed is:

An oar lock including an attaching plate, 75 a flange extending at right angles from the upper edge thereof, said flange and plate being adapted to bear upon the top and outer side edges respectively of the gunwale of a boat, there being openings in the flange and plate for the reception of fastening devices, 80 a sleeve integral with the plate and flange, said sleeve extending outwardly beyond the plate and upwardly beyond the flange, there being a counterbore extending downwardly 85 into the sleeve from its upper end, the lower end of the sleeve being beveled downwardly toward the plate and the upper end of said sleeve constituting a bearing, a bushing fitted within the counterbore, a yoke detachably 90 bearing on the upper end of the sleeve, a cylindrical pin extending from the yoke within the bushing, a portion of the upwardly extending end of the sleeve being positioned to overlie a portion of a gunwale 95 when seated in the angle formed by the plate and flange, thereby to reinforce the angle.

In testimony that I claim the foregoing as my own, I have hereto affixed my signature.

ANSON BORKERT.
